UNITED STATES PATENT OFFICE.

ERIK W. MIKAELSON, OF EASTON, PENNSYLVANIA, ASSIGNOR TO TREADWELL ENGINEERING COMPANY, A CORPORATION OF PENNSYLVANIA.

MANIPULATOR.

Application filed January 24, 1922. Serial No. 531,836.

This invention relates to a billet manipulator as associated with a rolling mill on the roller table for positively engaging and rotating a billet between passes.

5 An object of this invention is the production of a device of the type specified which will be of simple and rugged construction, economical to install and maintain, and sure and positive in its operation, and more especially intended for turning over rectangular billets in order to dispense with hand labor. While devices are known which work satisfactorily for the first passes when the billets are of comparatively large cross section, 10 hand labor is frequently necessary for the last passes because known devices of the lifting finger type are not suited to the shape and length of a small rectangular billet. This invention provides a device which is especially adapted for this purpose, which 15 now requires hand labor.

According to this invention, guiding means is positioned on the roller table to receive the billet from a pass and position 20 it ready to be turned 90° in its longitudinal axis, and then the table drops and the billet is automatically turned over or manipulated into position for the next pass. The manipulator of this invention is characterized by 25 the positive engagement of the billet at diagonal corners by separate engaging devices and rolling it over by relative opposite approaching movement thereof while so holding the billet, these devices then letting 30 go and moving out of the way so that the table can feed the billet to the next pass. The invention is applicable to various forms 35 of movable billet tables, a vertically bodily movable type being shown herein.

40 Other objects and advantages will appear from the description of the accompanying drawings, and the novel features of the invention will be particularly pointed out in the appended claims.

45 In the accompanying drawings:

Figure 1 is a plan view of a mechanism embodying my invention;

Figure 2 is a vertical sectional view on the line II—II of Figure 1;

50 Figure 3 is a vertical sectional view on the line III—III of Figure 1;

Figure 4 is a vertical sectional view on the line IV—IV of Figure 1;

55 Figure 5 is a fragmentary diagrammatic view showing the operation of rotating a

billet, the parts being viewed from the same position as the parts shown in Figure 4, and

Figure 6 is a similar view showing the final position.

The general arrangement of so much of 60 an ordinary table as suffices to show my invention is shown in Figure 1. This table has side beams 6 and 7, also shown in section in Figures 2, 3 and 4. The side beams at intervals support journal boxes 8, 9, 10, 11 65 and 12, shown in Figures 3 and 4. Within the journal boxes and supported thereby are the bearing ends of rollers 13, 14, 15, 16 and 17. In order to rotate these rollers a shaft 18, connected in any convenient or appropriate manner to a controllable motor is provided. Journals as 19 and 20 are provided for shaft 18 at proper intervals, and bevel gears as 21 and 22, are fastened to the shaft and mesh with bevel gears, as 23 and 24, fastened to the ends of the rollers, as 70 17 and 16. When shaft 18 is caused to rotate, a billet deposited on the right hand end of the table as viewed in Figure 1 will be moved in the direction of the arrow 25 of 80 Figure 1. I employ an I shaped cross beam 26, see Figure 2, to connect the two side beams at one point. This beam is connected to the side beams by brackets 27 and 28 and bolts 29. I also employ a specially formed 85 cross beam 30 for cross connecting the side beams through bolts 31. At still another point I connect the side beams 6 and 7 by special cross beams 32, attached by bolts 33. These cross beams support the billet manipulator. 90

On cross beam 26 is journal 34, shown in Figure 2; on cross beam 30 is journal 35, shown in Figure 3, and on cross beam 32 is journal 36 for supporting rocker shaft 37. 95

Rocker shaft 37 carries the two arm crank 38, one arm carrying weight 39, and the other a roller 40. Below roller 40 is a stationary cam member 41, held by bolts 42.

It is evident from Figure 2 that if the 100 table including side beams 6 and 7 and cross beam 26 is caused to rise and fall by the ordinary and well-known method, then when the table is in the position as shown in Figure 2, the crank 38 will be in the position shown in full lines in Figure 2, and when the table is lowered the crank 38 will assume the position shown in dotted lines in Figure 2. This rocks shaft 37 in the direction of arrow 43, Figure 2, when the 105 110

table drops and oppositely when the table rises.

The motion of rockershaft 37, in the direction of arrow 44 of Figure 3 is transmitted by crank arm 45, to link 46 and movable side guard 47 pivoted at 50 on bracket 74 of Figure 1, so that when the table is up, the side guard will be in the position as shown in full lines in Figure 3, but when the table is down the movable side guard 47 will be in the position as shown in dotted lines in Figure 3. This movable side guard has a roller 48 journalled in its lower end, resting on a platform 49, supported by cross beam 30 and positioned above the rolls. A billet travelling along the rolls will contact with guard 47 and be guided into a sort of throat formed by the inclined movable side guard 47 and a fixed inclined guide 51, shown in Figure 1. The fixed guide is supported adjacent one end by bracket 52, on I beam 53, supported on side beams 6 and 7, and adjacent the other end by bracket 54 supported on cross beam 30.

When a billet is advancing by the motion of the rollers 13, 14, 15, 16, etc., it is guided accurately by the fixed side guard 51 and the movable side guard 47 into the throat, into the position as shown by 55 of Figure 1, and the table is thereupon lowered which causes movable side guard 47 to be moved to the dotted line position as shown in Figure 3, out of the way of billet 55.

Simultaneously with movable side guard 47 being moved out of the way of billet 55, the billet is turned. To accomplish this, I provide a stop or abutment 56 against which the lower right hand edge of the billet, as viewed in Figure 4, may abut while force is laterally applied to the upper left hand edge of the billet to cause turning. The abutment 56 comprises a plate of tough steel fastened by screws 57 to lever 58. The lever 58 is pivoted on pin 59 journalled in a bracket 60 supported by side beam 7 and cross beam 32. When the table is in upper position, the lever 58 is in the position as shown in full lines in Figure 4, but when the table is lowered the lever 58 is raised to the position shown in Figure 5. Figure 6 shows the final position. In order to raise the lever when the table falls, I provide the left hand under end of the lever with a cam surface 61 against which the roller 62 journalled in the end of lever 63 bears. When lever 63 turns on its pivot 64, journalled in cross beam 32, the roller 62 riding against cam surface 61, forces lever 58 into the positions shown in Figures 5 and 6.

The movement of crank 63 is simultaneous with that of lever 65, rigidly fastened to shaft 37, by reason of link 66 connecting the two. The lever 65 forms a pivot for turning head 66 by pin 67, the lever 65 shown in Figs. 5 and 6, fitting between the

bifurcated end of the head 66, so that simultaneously with the movement of lever 58 upwardly, as in Figure 4, the turning head 66 starts to move. The head 66 consists of a broad flat bottomed casting, with the side at 70 which the billet enters rounded upward like a shoe to prevent interference with the end of the billet. The path of movement of head 66 is controlled by lever 65 and cam surface 68 of cam block 69 supported by cross beam 32, so that upon movement of lever 65 to the right, as in Figure 4, by reason of lowering of the table, the head 66 moves downward until it reaches a position slightly succeeding that of Figure 4 with 80 the guide 47 drawn back and head 66 resting on the billet. Shoulder 70 contacts with the upper left hand edge of billet 55, and shoulder or abutment 56 of lever 58 with the right hand lower edge. The head 66 now continues to move to the right and the billet is turned over 90°. After the billet is turned, the head 66 swings upward and lever 58 downward, see Figure 6, with the billet on rollers 13, etc., ready to be fed into the next 90 pass. After the billet has gone through this pass, upon raising the table, the parts have the positions shown in Figures 3 and 4, ready for the next billet. While lever 58 preferably does not move laterally as head 95 66 moves oppositely, the important feature is the relative opposite movement between these parts, and I intend to cover such movement broadly.

As shoulder 70 has a very heavy duty to 100 perform I prefer to form this shoulder of a block 71 of tough and wear-resisting material such as manganese steel, set into lever 66 and held therein in place by set screw 72, fastened by lock nut 73. A similar construction is used for plate 56.

This mechanism replaces hand labor and effectually turns rectangular billets which previous devices used only for early passes do not handle, and which so far as I am 110 aware, simply rely on a finger or fingers for turning the relatively short billet over by lifting one edge, whereas this mechanism positively acts on diagonal corners of the billet, very much in the manner of the long 115 hand wrench now used by the rollers where the cross section is reduced. Where I say corner, I do not restrict myself to the exact corners, but mean to include, as herein shown, a turning engagement on opposite 120 sides in different planes, it being obvious that the greatest turning moment is with the engagement as near diagonal corners as possible.

Various modifications and changes may be 125 made without departing from the scope of the appended claims.

What I claim is:

1. In a billet manipulator, the combination with a roller table, of an abutment 130

- adapted to engage a lower corner of the billet, means for guiding the billet into a position for cooperation with said abutment as said billet is moved over the table, and 5 means laterally movable relative to said abutment, adapted to engage a diagonally opposite corner of the billet for turning it about said abutment.
2. In a billet manipulator, the combination with a roller table, of means extending longitudinally of the table for guiding a billet into position to be turned, and automatic means for laterally moving at least a portion of said guiding means to permit the 10 billet to be turned over for the next pass.
3. In a billet manipulator, the combination with a table comprising a plurality of rollers, of abutments located between rollers, and adapted to engage diagonally opposite corners of the billet, mechanism for producing relative movement between said abutments and means laterally toward each other to turn the billet without lifting the same off the table.
- 25 4. In a billet manipulator in combination with a roller table, an abutment engaging a corner of a billet to be turned, means for moving the abutment into and out of operative position, and laterally movable means 30 engaging the opposite diagonal corner for turning the billet on the abutment as center.
5. In a billet manipulator in combination with a vertically movable roller table, a rigid cam positioned beneath the table, 35 and means operated by the cam upon a movement of the table for rotating a billet on its longitudinal axis.
6. In a billet manipulator, the combination with a roller table, of a guide means 40 for directing a billet being moved over said table, means for removing said guide means from adjacent said billet, an abutment adjacent the lower edge of a billet after being moved into position by said guide means, 45 means for raising said abutment relative to the table after removal of said guide means and for lowering said abutment after the billet has been turned, and transversely movable means engaging a diagonally opposite corner of a billet from said abutment for turning said billet about said abutment.
- 50 7. In a billet manipulator, the combination with a roller table, of a guide means for directing a billet while being moved over said table, means for removing said guide means from beside a billet, an abutment adjacent the lower edge of a billet after being moved into position by said guide means, 55 means for raising said abutment relative to the table after removal of said guide means and for lowering said abutment after a billet has been turned, a transversely movable head mounted above said table to be raised and lowered relative thereto, and means movable with said abutment for simultaneously
- lowering said head and transversely moving the same to engage billets of different sizes at the diagonally opposite corner from said abutment.
8. In a billet manipulator, the combination with a roller table, of an abutment transversely fixed relative thereto and projecting above the surface of the table to engage the lower corner of a billet, a head pivotally mounted above said table for movement up and down and transversely of the table, a shoulder in said head shaped to engage a corner of a billet and means for moving said head to engage billets of different sizes at a corner diagonally opposite the abutment and turn the billet about said abutment.
- 70 9. In a billet manipulator in combination with a roller table, billet guiding and positioning means comprising a fixed guide on the table and a movable guide on the table 75 and controlled by the table position; and an abutment engaging a corner of a billet to be turned, and a laterally movable means engaging the opposite diagonal corner for turning the billet on the abutment.
10. In a billet manipulator in combination with a roller table, a pivoted guide inclined lengthwise of and carried by the table; means operated by a movement of the table for swinging the guide, and a fixed 80 inclined guide carried by the table above the rollers and cooperating to form with the movable guide a contracting passageway ending a throat for a billet, and billet turning means between said guides.
- 85 11. In a billet manipulator, a lever formed with a shoulder, a pivot for the lever, means for swinging the lever to bring the shoulder into engagement with the edge of a billet; a second lever formed with a shoulder; means for supporting and swinging the said second lever so that the shoulder will engage a diagonally opposite edge of the billet and turn on the shoulder of the first lever.
- 90 12. In a billet manipulator a lever journaled intermediate its ends, a second lever pivoted on one end of the first lever and formed with a shoulder; a cam positioned below the second lever; a roller journaled in the second lever and bearing on the cam, 95 and means for operating the first lever whereby the second lever is moved in a path governed by the cam to engage a corner of the billet and the shoulder of the first lever engages a diagonal corner of the billet to rotate it.
- 100 13. In a billet manipulator a lever journaled intermediate its ends, a second lever journaled intermediate its ends, a link connecting one end of the first lever with one end of the second lever and means operated by the levers for rotating a billet.
- 105 14. In a billet manipulator, a lever journaled intermediate its ends, a second lever journaled intermediate its ends, a link con- 110
- 115
- 120
- 125
- 130

necting one end of the first lever with one end of the second lever, a third lever formed with a shoulder, a pivot for the third lever, a fourth lever formed with a shoulder, a 5 pivot in the free end of the first lever for the third lever, a cam positioned beneath the third lever, an arm on the third lever bearing on the cam positioned thereunder, and means for operating the first lever, whereby 10 the second lever is moved to actuate the fourth lever, and the fourth lever moves in a path governed by the second lever and whereby a billet is caught at diagonally opposite edges between the shoulder on the 15 third lever and the shoulder on the fourth lever and rotated.

15. In a billet manipulator, the combination with a roller table, of means movable with respect to said table for turning the 20 billet thereon, and inclined guiding means for directing the billet into cooperation with said first mentioned means, said guiding means being movable out of the way of said first mentioned means and billet in 25 turning.

16. In a billet manipulator, two pivoted levers each formed with a shoulder and means including cams whereby said levers are simultaneously moved to engage a billet 30 between the shoulders on diagonally opposite corners and rotate it.

17. In a billet manipulator in combination with a movable roller table, a cam, an arm carried by the table and bearing against 35 the cam whereby when the table is moved the arm oscillates; and means operated by the arm for engaging opposite corners of a billet and rotating it.

18. In a billet manipulator in combination 40 with a movable roller table, a cam, an arm bearing on the cam whereby when the table is moved the arm oscillates, and means operated by the cam for positioning the billet and for engaging the billet at opposite corners and rotating it.

19. In a billet manipulator in combination 45 with a movable roller table, a cam positioned beneath the table; a longitudinal shaft supported by the table; an arm on the shaft and

bearing on the cam, whereby when the table 55 is moved the arm and the shaft oscillate; and means operated by the shaft for rotating the billet.

20. In a billet manipulator, the combination 60 with a roller table, of an abutment adapted to engage a lower corner of the billet, and means movable both upwardly and laterally through said table for engaging a diagonally opposite corner and turning the billet about said abutment without 65 lifting it off the table.

21. In a billet manipulator, a roller table 70 to receive billets from a pass and convey them to another pass in a different plane, means for guiding the billet as delivered from the first pass to position for turning over, and means engaging opposite corners 75 of the billet for turning it upon movement of the table for the next pass.

22. In a billet manipulator, the combination 75 with a roller table, of guide means for directing the billet into position to be turned, an abutment adapted to engage a lower corner of the billet, means adapted to engage a diagonally opposite corner of said 80 billet, mechanism for moving at least a portion of the guide means out of the way, and for moving said abutment into position, and mechanism for automatically producing relative lateral movement between the abutment 85 and means engaging the diagonally opposite corner of the billet.

23. In a billet manipulator, the combination 90 with a table comprising a number of rollers, of an abutment located between said rollers adapted to engage the corner of the billet, a shouldered member mounted for pivotal movement in a substantially vertical plane and adapted to engage a diagonally opposite corner of a billet, and 95 mechanism for producing relative lateral movement of said abutment and shouldered member toward each other to turn the billet without lifting the same off the table.

Signed at Easton, in the county of North- 100 ampton, and State of Pennsylvania this 17th day of January A. D. 1922.

ERIK W. MIKAELSON.
